UNITED STATES PATENT OFFICE.

CARL ROSIER, OF DUSSELDORF-RATH, GERMANY.

IRONING-MACHINE.

1,147,121.

Specification of Letters Patent. Patented July 20, 1915.

Application filed November 3, 1914. Serial No. 870,022.

To all whom it may concern:

Be it known that I, CARL ROSIER, a subject of the German Emperor, and resident of 344 Theodorstrasse, Dusseldorf-Rath, Germany, engineer, have invented certain new and useful Improvements in Ironing-Machines, of which the following is a statement.

The present invention relates to an ironing machine which is characterized by the fact that one of the ironing members, ironing shoe or ironing table is rotatable and that the ironing shoe has on its circumference recesses of various sizes, corresponding in shape and size with the various lengths of the shirt collarbands. This arrangement of the ironing machine affords the advantage that when the rotatable member is correspondingly set, it is possible to iron with the same ironing shoe shirts and shirtfronts of various collar lengths. Hitherto this was not possible with the known machines, as only one shirt front of a given size could be ironed with the same ironing shoe.

In the accompanying drawing two constructional forms of the ironing machine are exemplified.

Figure 1 is an elevation of the one constructional form of the machine. Fig. 2 is a vertical section through the upper part of this machine. Fig. 3 is an elevation of the second constructional form of the machine and Fig. 4 is a vertical section through the upper part of this latter machine. Fig. 5 is a view of the device for securing the collarband to the ironing table and Fig. 6 is a top view of the ironing shoe alone.

The ironing shoe 1 has in both constructional forms of the machine a plurality of semicircular recesses 2 in its periphery, the said recesses differing in size and corresponding to the various lengths of the collarbands occurring. In both constructional forms the ironing shoe is rotatably fitted to its carrier, so that each of the recesses 2 can be adjusted over the clamping device for holding the collarband.

In the first constructional form of the machine the hollow ironing shoe 1 has a hollow stud 3, which is revolvably fitted in the body 4 of the machine. Below this stud 3 has a flange 5 and above it has a thread on which is screwed a nut 6. Into this stud 3 projects a tube 7, which is packed by means of a stuffing box 8 and which is at the top connected to a bend 9, which again

connects with a supply pipe 10 for the heating steam. Within the said tube 7 is fitted a longer pipe 11, which extends down to the bottom of the ironing shoe and is closed at the top by a flange. This flanged end 12 is connected to a pipe 13, which serves to drain off the condensation water accumulating within the ironing shoe. The body 4 is supported by posts 14, which are secured to the base 15. On this base is disposed a sleeve 16, in which a thick pin 17 is slidably fitted, which pin may be raised and lowered in known manner by means of the device disclosed in the United States patent to Friedrich Krapp 913,296, Feb. 23, 1909, and shown in Fig. 1, by aid of the footlevers 18 and 19.

On the one post 14 is slidably fitted a sleeve 20 which in its lowermost position bears on a ring 21 clamped in a stationary position. This sleeve 20 has an arm 22, the end of which forms the bed for the ironing table 23 sliding thereon. This ironing table is coupled by means of a rod 24 with a double-armed lever 25 pivotally fitted to the sleeve 20, the upper end of which lever 25 carries a roller 26, which engages in a slot 27 having the shape of the mantle of a cone. When the pin 17 is raised, it bears against the underside of the arm 22 and lifts the latter together with the ironing table and the sleeve 20, so that the ironing table is pressed against the ironing shoe and is simultaneously advanced owing to the rotation of lever 25 by slot 27. Thereby the ironing effect is obtained.

On the ironing table is fitted the device for clamping the shirt. It consists of a semicircular angle 28 secured to the upper side of the ironing table. In this angle a bracket 29 is fitted, which has two holes 30 on its upper side. Into these holes two pins may be inserted, which are fitted to the bar 32, held by means of a thumbscrew 33 to the clamping strap 31. The clamping strap is placed over the angle and pressed against the latter by the turning of an eccentric 100 acting on the bracket 29; the elastic strap thereby bears from outside against the collarband, which is thus pressed against the angle 28. The ironing table is covered with a cloth 34. A second clamping strap 36 is also provided, which is by means of arms 37 pivotally fitted to the shaft 38. These arms 37 are coupled to an arm 39 the free end of which grasps a rod 40, the one end of which

carries a collar 41, while the other end is linked to a lever 42. Between the arm 39 and the collar 41 a spring 43 is fitted to rod 40 and the lever 42 pivotally fitted to sleeve 20 is provided at its other end with a handle 44. During the upstroke of lever 42 the rod 40 is likewise raised, whereby by aid of spring 43 the curved bar 36 is pressed against the edge of the ironing table, so that the shirt drawn over the ironing table is clamped on this side. At the opposite end of the ironing table a polygonal shaft 45 is revolvably journaled. On this shaft 45 is fitted a ratchet wheel 46, in which engages a pawl 47. The lower end of the shirt is laid around this shaft and wound thereon by turning the shaft, whereby the shirtfront is pulled taut over the ironing table. The pawl 47 will then hold the shaft 45 so long 20 in such position until it is disengaged from the ratchet wheel by means of handle 48 and the shaft can turn backward to unwind the shirt.

On the second post 14 a second similar 25 ironing table may be fitted, or several arms 22 with ironing tables disposed in the shape of a star may be fitted to the one sleeve 20. The provision of several ironing tables has the advantage that while one shirt is being 30 ironed a second may be fixed onto the next ironing table.

The curved angle 28 is fitted easily detachable from the ironing table, so that the various angles, corresponding to the various collarband widths may be readily fitted. Then the ironing shoe is turned so far until the respective recess 2 is over the angle 28 so that the shirt drawn over the table will be ironed perfectly smooth.

40 In the constructional form of the machine shown in Figs. 3 and 4 the ironing table does not rise and fall, but the ironing shoe does. The ironing shoe 1 is secured by means of screws 50 to the round plate 51 which carries 45 a hollow stud 52 pointing upward, which projects revolvably through an annular disk 53 and is held in such position by means of a ring 54 screwed on it. Through the said hollow stud projects a tube 55, which is 50 packed by means of a stuffing box 56. This tube 55 has at its top a connection piece 57 for receiving a rubber tube or some other flexible tubing. Through tube 55 extends a pipe 58 which likewise has a connection 55 piece 59 at its top for connection to a flexible tubing. Through tube 55 the hot steam is supplied to the ironing shoe and through pipe 58 the condensation water accumulating in the ironing shoe is drained off. The ironing shoe 1 carries a ring 60 with which it can be turned. The annular plate 53 is supported movably by the strap 62 and two links 61 hinged to it. The strap 62 has a long sleeve 63 which is arranged to slide in 60 the body of the machine 64. In this sleeve

63 is fitted loose a plate 65, which may, by means of a screw 66 be vertically adjusted. The screw 66 bears with a collar 67 against the strap 62 and it has below a square 68, by means of which it can be turned. Against 70 this plate bears a spring 69, on which lies from above a likewise loose disk 70, on which a slide 71 rests, against which a plate 72 bears from above, which is held by a screw 74 in the lid 73 of the sleeve 72.

75 The slide 71 has a recess into which the cylindrical end 75 of the lever 76 projects which is journaled on the shaft 77 in the machine body 64, and the other arm of which is made in the shape of a frame 78 80 which encircles a cam disk 79. This cam disk 79 is fitted to the shaft 80, which carries a toothed wheel 81, which engages in a toothed wheel 83 fitted to shaft 82. This shaft 82 is driven by means of belt pulleys 85 fitted on it. By the rotation of the cam disk 79 the lever 76 is rocked to and fro, so that the sleeve 83 and with it the strap 62 and the ironing shoe are raised and lowered. In the toothed wheel 83 also engages 90 a toothed wheel 86 fitted to the shaft 85, so that also this shaft is revolved, on which a cam disk 87 is fitted which is encircled by a frame 88 rockingly fitted to shaft 89. To frame 88 is linked a rod 94 which is coupled 95 by means of pin 90 to the annular plate 53. When the shaft 82 is revolved thus also the frame 88 is rocked to and fro and thereby the annular plate 53 and the ironing shoe 1 are reciprocated, the annular plate rocking 100 on the links 81.

Beneath the ironing shoe the ironing table 91 is arranged. It is fitted to a rotatable plate 92 on which any desired number of ironing tables may be fitted. The plate 105 92 is supported under the ironing shoe by means of post 93, so that the pressure produced in ironing is not transmitted to the shaft of plate 92. While one shirt is being ironed a second shirt may be fixed on one 110 of the other ironing tables. The device for clamping the shirt to the table is the same as described hereinbefore with reference to the first constructional form. It has not been shown in Figs. 3 and 4, and neither 115 has it been shown in Fig. 1.

I claim:

1. Machine for ironing shirts, consisting of a rotatable ironing shoe, said ironing shoe having several differently shaped recesses for the collarband, an ironing table arranged below the said ironing shoe, adapted to receive the shirt to be ironed stretched thereon, a heating arrangement for said ironing shoe, means for producing a relative movement of said ironing shoe and said ironing table.

2. Machine for ironing shirts consisting of an ironing shoe arranged to rise and fall and revolve, said ironing shoe having sev- 130

eral differently shaped recesses for the collar band, an ironing table disposed beneath said ironing shoe with means for clamping the shirt thereto and stretching the same thereon, means for raising and lowering the said ironing shoe and means for sliding said ironing shoe to and fro.

3. Machine for ironing shirts consisting of a rotatable ironing shoe, a plurality of ironing tables fitted to a rotatable plate, means for clamping the shirt to and stretching the same on the ironing table, a lever, a frame and a driven cam disk for raising and lowering the ironing shoe, a frame and a driven cam disk for reciprocating the ironing shoe.

4. Machine for ironing shirts consisting of an ironing table, an ironing shoe adapted

to rise and fall and reciprocate, means for heating the ironing shoe, a vertically sliding strap, said strap adapted to movably hold the ironing shoe by aid of links, a lever for vertically reciprocating said strap, a frame coupled to said lever, said frame adapted to be reciprocated by a driven cam disk, and a frame reciprocated by a cam disk, and linked by means of a rod to the said ironing shoe.

In testimony whereof I have hereunto set my signature in the presence of two witnesses.
